020-22

EX

OR D 24,181

DESIGN.

—o—
L. B. MAY.
LABEL.

No. 24,181.

Patented Apr. 9, 1895.

Witnesses _____ Inventor,
Robert S. Sanger Louis B. May,
Charles H. Rice by J. C. Clayton, atty.

UNITED STATES PATENT OFFICE.

LOUIS B. MAY, OF NEW YORK, N. Y., ASSIGNOR TO THE AMERICAN GROCERY COMPANY, OF JERSEY CITY, NEW JERSEY.

DESIGN FOR A LABEL.

SPECIFICATION forming part of Design No. 24,181, dated April 9, 1895.

Application filed January 31, 1895. Serial No. 536,886. Term of patent 14 years.

To all whom it may concern:

Be it known that I, LOUIS B. MAY, a citizen of the United States, and a resident of New York city, in the county of New York and State of New York, have invented and produced a new and original Design for Labels, of which the following is a specification, reference being had to the accompanying drawing, which illustrates the design.

- 10 The leading feature of the design consists of a label having its top portion and one side formed of inwardly curved lines joined by short straight lines at each intersection, while the remaining side has a curved line at its 15 upper portion from the lower extremity of which commences a convexity which sweeps with a bold swing past the central line of the label and joins the lower curve at the opposite side by a short straight line.
- 20 The general shape of the label somewhat resembles a heraldic escutcheon, but it is not symmetrical. It has nine sides. The upper side a is a curved line, so that the top of the label is concave. From the left hand end of 25 line a, there extends downward, and more to the left, a short straight line b. From end of line b there is a longer inwardly curved line c. From the lower end of line c, there sweeps with a bold swing to the right, the long reversed curved line d. From the right end of line d, there rises toward the right, a very short straight line e. From e there extends upward, and a little to the right an inwardly curved line f. From the upper end of line f, there extends a short straight line g, inclined 30 a little outward. From the upper end of line g there springs a bold curved line h inclined considerably to the left, where it meets a short straight line i, which is further inclined to the left, and then joins the right-hand end of line a. 35 40

I claim—

The design for a label substantially as herein shown and described.

Signed at New York, in the county of New York and State of New York, this 30th day of January, A. D. 1895.

LOUIS B. MAY.

Witnesses:

J. C. CLAYTON,
F. S. BRIGGS.